UNITED STATES PATENT OFFICE.

GEORGE W. ANSLEY, OF SPOKANE, WASHINGTON

HAMMER ATTACHMENT.

1,017,491.

Specification of Letters Patent. Patented Feb. 13, 1912.

Application filed October 4, 1911. Serial No. 652,892.

To all whom it may concern:

Be it known that I, GEORGE W. ANSLEY, a citizen of the United States, residing at Spokane, in the county of Spokane and 5 State of Washington; have invented certain new and useful Improvements in Hammer Attachments; and I do hereby declare the following to be a full, clear, and exact description of the invention, such as will enable others skilled in the art to which it 10 pertains to make and use the same, reference being had to the accompanying drawings, and to the letters and figures of reference marked thereon, which form a part of this 15 specification.

This invention relates to new and useful improvements in nail extracting devices for attachment to hammers, etc., and consists in the provision essentially of a hammer 20 head having a slot therein with inclined walls in which the shank portions of claw members are adapted to be pivotally mounted and so arranged that, when the claws are brought into engagement with a nail and 25 the handle of the hammer thrown in the act of drawing the nail, the jaws will be caused to securely clamp the nail and extract the same.

The invention comprises various details 30 of construction and combinations and arrangements of parts which will be herein-after fully described, shown in the accompanying drawings and then specifically defined in the appended claims.

35 I illustrate my invention in the accompanying drawings, in which:—

Figure 1 is a side elevation. Fig. 2 is a view showing the claws removed. Fig. 3 is a detail perspective of the claws, and Fig. 40 4 is an end view showing the claws held together. Fig. 5 is a bottom plan view of the device.

Reference now being had to the details of the drawings by letter, A designates the 45 hammer head having a socket portion B. Said head is provided with a slot D, the opposite walls D' of which are inclined to each other. Said walls are apertured at F, and H, H designate two jaws, each having 50 a shank portion K, the outer faces of which K' are inclined and terminating in shoulders L. Said shank portions are apertured at O for the reception of the pin which is adapted to be passed through registering 55 apertures in the walls of the head and said shank portion and forming a pivotal con-

nexion between the jaws and head. The adjacent faces of each jaw are provided with serrations Q and said edges are inclined.

S is a spring arranged to press the jaws outward in the slot.

When the parts are adjusted in place, the jaws of the hammer are placed on either side of the nail and made to contact therewith and, when the handle of the hammer is swung in one direction, it is adapted to cause the inclined faces of the jaws to have a wedging action against the inclined walls of the slot, thereby throwing the serrated 70 edges of the jaws frictionally against the nail and gripping the same securely. A reverse movement to the handle will cause the jaws to release their grip upon the nail.

By the provision of a hammer made in 75 accordance with my invention, it will be noted that a simple and efficient means is afforded whereby a nail may be securely and positively gripped to hold the nail while being extracted and easily and conveniently released when the nail is withdrawn.

Attention is called to the fact that the free exposed ends of the jaws permit them to engage a nail placed adjacent a perpendicular surface as at a corner of a room which they could not if the slotted head projected beyond the jaws. The extension of the jaws inward beyond the nail engaging hollow portion thereof lessens the leverage upon the pivot of the tilting out action of the jaws in drawing a nail.

What I claim to be new is:—

1. A nail extracting device having a head with a curved fulcrum forming surface having a slot running in from one end, jaws having reduced portions or arms pivoted to said head and each other at their inner ends at the inner end of said slot, the body of said jaws extending from the end of the 100 head and forming nail drawing claws with exposed free ends, the outer faces of said jaws and the walls of said slot being inclined so that outward movement of the jaws through the slot tends to press the 105 jaws toward each other, the inner faces of the claw part of the jaw being hollowed out to form nail pinching edges which do not extend any substantial distance into the slot of the head, substantially as described.

2. A nail extracting device having a head with a curved fulcrum forming surface hav-

ing a slot running in from one end, jaws having reduced portions or arms pivoted to said head and each other at their inner ends at the inner end of said slot, the body of 5 said jaws extending from the end of the head and forming nail drawing claws with exposed free ends, the outer faces of said jaws and the walls of said slot being inclined so that outward movement of the jaws 10 through the slot tends to press the jaws toward each other, the inner faces of the

claw part of the jaw being hollowed out to form nail pinching edges which do not extend any substantial distance into the slot of the head, and a spring tending to press 15 the jaws outward in the slot.

In testimony whereof I hereunto affix my signature in the presence of two witnesses.

GEORGE W. ANSLEY.
